UNITED STATES PATENT OFFICE.

HENRY W. KOISTINEN, OF ERWIN, SOUTH DAKOTA.

FANNING MILL AND GRADER.

Application filed August 6, 1925. Serial No. 48,645.

My invention relates to improvements in fanning mills and grain cleaners and graders in which a series of sieves operate in conjunction with revolving aprons above such 5 sieves and stationary cross slats below the sieves, and the objects of my improvements are:

1. To provide means for steady and uniform feeding of grain over sieves.
2. To provide for removable aprons, sieves and stationary cross slats.
3. To provide for successive operations of cleaning and grading so as to give the sieves better opportunity to do effective work.
4. To provide 15 for the cleaning of grain five times in one continuous operation.

I attain these objects by the mechanisms shown in the accompanying drawings, in which Figure I is a vertical, longitudinal 20 section of the interior mechanism showing aprons, cross slats, and series of sieves and other parts necessary to show operation of machine. Figure II is a view of right side of machine. Figure III is a view of the left 25 side of the machine.

Figure IV is a view of the front side of the machine; Figure V represents part of crank shafts and also the crank on one side; the other crank not shown.

30 Similar numerals refer to similar parts throughout the several views. The letter A, whenever used, refers to outside frame of the machine. The letter B refers to the interior framework or shaker shoe containing 35 the first series of sieves. The letter C refers to the interior framework of the shaker shoe containing the second series of sieves. The letter D refers to the interior framework of the shaker shoe containing the third 40 series of sieves.

The framework A' supports the hopper and feeder of grain which is fitted with the sliding board A², allowing opening and closing of the opening I to permit grain to feed 45 downwardly upon the shaker shoe board B³. The sliding board A² is fitted with the cogs A³ which are engaged by the cogs 2 on the cogged wheel 3. The cogged wheel 3 is keyed to the shaft 4 which passes through 50 suitable boxings on the frame posts A²³. At the outside of the frame posts A²³ is attached the lever 5. It will be noted that the sliding board A² may be moved downwardly or upwardly by a corresponding movement of the 55 lever 5. The lever 5 is fitted with the catch 6 to hold the lever 5 on the cogged frame-

work 7 in whatever position placed. The hopper A¹ is also fitted with the shaft 9 five inches above the opening I. The shaft 9 runs through suitable boxings in the frame 60 A. To the shaft 9 is attached the pulley 10. The shaft 9 is, therefore, operated by means of the belt 11 passing over the pulley 10, as indicated in Figure III. The shaker shoe B is fitted with the sieves B², B³, and B⁴. The 65 shaker shoe B is given the shaker movement by means of the shaker arm B⁵, attached to the shaker shoe B at the pin B⁶ and fastened to the crank shaft 13 at the crank portion B⁷. While the drawings illustrate only the one 70 shaker arm B⁵, I call attention to the fact that my machine is equipped with double arms, one at either side of the shaker shoe B and operating on the crank shaft 13, as indicated. The crank shaft 13 passes through 75 suitable boxings in the frame A and is fitted on the outside of the frame A with the pulleys 14 and 15 properly keyed to the crank shaft 13. The crank shaft 13 is, therefore, operated by means of the belt 16 passing 80 over the pulley 14.

To the frame A at A⁴ is fastened the adjustable framework A⁵ to contain the endless aprons 17, 18 and 19 and the cross slat cleaner 20. It will be noted that the framework 85 A⁵ is fastened to the frame A by the removable pins A⁴. The frame A⁵ is fitted with holes, as indicated, to allow adjustment of the frame A⁵. It is also noted that the frame A is so constructed to allow the adjustment forwardly and backwardly on the frame A of the removable pins A⁴. The endless aprons 17, 18 and 19 revolve over the rollers 25, which rollers 25 are fastened to suitable shafts set in suitable boxings in the 90 frame A⁵, as indicated, at the boxings 26. The endless aprons 17, 18 and 19 are operated by the pulleys 27, 28 and 29, respectively, keyed to the three upper rollers 25. The pulley 27 is operated by the belt 30 passing 95 over the pulley 27 and the pulley 31. The pulley 29 is operated by the belt 32 passing over the pulley 29 and the pulley 10. The pulley 10 is a double pulley allowing the use of the belts 11 and 32, as indicated. The pulley 29 is a double pulley allowing the use of two belts as indicated. Thus, it will be noted that the pulley 29 serves to drive the pulley 28 by means of the belt 33.

The frame A⁵ serves as a framework fitted with the tracks A⁶ to carry the rollers B⁸ which are appropriately fastened to the

shaker shoe B. It will be noted that the frame A⁶ serves as a carrier for the shaker shoe B by the movement of the rollers B⁸ on the tracks A⁶ at the slots A⁷. The cross slats 20 are fastened in the frame A⁶ by the rods A⁸.

It will be noted that the grain passing through the opening I falls upon the board B¹ of the shaker shoe B which carries the grain downwardly along the board B¹ to the sieves B², B³ and B⁴, respectively. As the grain passes down the sieve B², the endless apron 17 passes downwardly over the sieve B² keeping the sieve B² clean and carrying the grain evenly over the sieve B². As the grain passes through the sieve B² it falls on the endless apron 18 and is carried upwardly and over to the upper end of the sieve B³, repeating the operation in the same manner as on the sieve B². As the grain passes through the sieve B³, it falls on the endless apron 19 and is again carried to the upper end of the sieve B⁴, and the operation is again repeated in the same manner as on the sieves B² and B³, respectively. The stationary cross slats 20 under the sieve B⁴ serve to keep the sieve B⁴ from becoming clogged, at the same time allowing the grain to fall through the sieve B⁴ and between the cross slats 20 upon the board B⁹ which carries the grain downwardly to the lower end of the board B⁹ where the grain drops to the sieve C¹ fitted into the shaker shoe C. It will be noted that coarse chaff, straw and dirt from the grain passes over the sieves B², B³, and B⁴, respectively, and is carried out of the machine at the lower end of the shaker shoe B at the boards B¹⁰.

The shaker shoe C is fitted with the rollers C² fastened respectively to the shaker shoe C by the pins C³. The rollers C² pass through the slots A⁹ in the frame A and the rollers C² rest on the tracks A¹⁰ which serve as carriers for the shaker shoe C and allow shaking movement of the shaker shoe C. The shaker shoe C is operated by the shaker arm C⁴ fastened to the shaker shoe C by the pin C⁵. The shaker arm C⁴ is fastened to the crank shaft 34 at the boxing C⁶. The shaker shoe C is also fitted with double shaker arm C⁴ in the same manner as the shaker shoe B. The crank shaft 34 passes through suitable boxings in the frame A. At the ends of the crank shaft 34 is fastened the pulleys 35 and 36, respectively. The crank shaft 34 is operated by the belt 37 passing over the pulleys 35 and 38.

The grain, after falling upon the sieve C¹, passes downwardly over the sieve C¹ which is kept clean by the cross slats supported on rods A¹². The screenings passing through the sieve C¹ fall between the cross slats A¹¹ upon the board C⁷ and are carried back over the lower end of the board C⁷ into the con-

veyer 39. The conveyer 39 is fitted with the auger 49 so constructed to carry the screenings from the center of the conveyer to both sides of the machine. At each end of the conveyer 39 are the pipes 48 to carry the screenings to the shaker shoe D, as indicated. The grain passing over the sieve C¹ falls upon the board C⁸ which carries the grain downwardly over the end of the board C⁸ to the shaker shoe D. As the grain falls from the lower end of the board C⁸ to the sieve D¹, the grain is cleaned of dust and chaff by means of the air blast from the fan casing A¹³.

The shaker shoe D is fitted with the rollers D² by the pins D³. The rollers D² pass through the slots A¹⁴ and rest on the tracks A¹⁵ which serve as a carrier for the shaker shoe D and allow the shaker movement of the shaker shoe D, as indicated. The shaker movement of the shaker shoe D is given by the shaker arms D⁴, pivoted link D⁵ and shaker arm D⁶ which are at both sides at inside. The shaker arm D⁴ is fastened to the shaker shoe D by the pin D⁷ and the shaker arm D⁶ is fastened to the crank shaft 40 at the boxing D⁸. The crank shaft 40 passes through suitable boxings in the frame A at the right side of the machine. To the crank shaft 40 is fastened the sprocket 41 and the crank shaft 40 is operated by means of the chain 42 passing over the sprocket 41 and the large drive sprocket 43. The connecting pivoted arm D⁵ is fastened to the shaker arms D⁴ and D⁶, respectively, at the pins D⁹, while the shaker arm D⁵ is fastened to the frame A by the pin A¹⁶.

As the grain passes over the sieve D¹, it moves downwardly over the lower end of the board D¹⁰ delivering the cleaned and graded grain at the back of the machine at X. Any screenings that might be left in the grain as it passes over the sieve D¹ falls through the sieve D¹ and between the cross slats A¹⁷ on the sieve D¹¹. It will also be noted that the screenings that pass from the conveyer 39 through the pipes 48 are deposited on the sieve D¹¹ and are carried downwardly over the sieve D¹¹ and over the board D¹² and are carried out of the machine at the point Y. The sieve D¹¹ should be of the kind that will permit all screenings to pass between same and through the cross slats D¹⁸ so that all screenings will be delivered out of the machine at the point Z at the lower end of the board D¹³.

On the crank shaft 40 is fastened the fan 44 to provide for air blast to clean grain, as indicated. At each end of the drum A¹³ are vents A¹⁹ to allow air to enter drum. The upper part of the drum A¹³ is fitted with a hinged cover A²⁰ which may be closed or opened in order to regulate air blast between the shaker shoes C and D. To the back part of the frame A at the point A²¹ is a hinged

board cover A²² which may be removed or closed or opened as desired by the operator of the machine. The motive power for the machine is supplied by hand operation of the main sprocket wheel 43 at the handle 45, or, if desired, suitable arrangements may be made for providing pulley for power driving, if necessary. The sprocket wheel 43 drives the crank shaft 40 and the fan 44 and also supplies the power to drive the crank shaft 34 by means of the belt 37, as illustrated in Figure III. To the crank shaft 34 is fastened the pulley 36 which drives the pulley 14 by means of the belt 16 and operates the mill and grader, as hereinbefore explained. The sprocket wheel 43 revolves on the end of the crank shaft 34 to the outside of the pulley 36, i. e., the crank shaft 34 extends beyond the pulley 36 so as to serve as the shaft on which the sprocket 43 revolves. The auger 30 is operated by means of the belt 46 passing over the pulley 47 on the auger 30 and passing over the double pulley 15.

25 While the plan of my invention provides for the removal of endless aprons and stationary cross slats and sieves and allows several series of sieves and stationary cross slats, nevertheless I prefer to carry out my invention in the form as herein explained, providing for three sieves in the shaker shoe B with three endless aprons above such sieves, respectively, and the stationary cross slats under the third sieve of the shaker shoe B and a similar sieve in shaker shoe C fitted with stationary cross slats under the sieve in shaker shoe C and two sieves in shaker shoe D fitted with stationary cross slats under the sieve of shaker shoe D. The sieves of shaker shoe B are designed to carry off course chaff and coarse foul seed. The sieve of shaker shoe C is designed to serve as a grader, removing smaller foul seed and grain from the grade of grain desired. The sieves of shaker shoe D are designed to serve in grading the grain and remove from the better grades all screenings and small foul seed.

40 I am aware that prior to my invention fanning mills and grain cleaners have been made with series of shaker sieves and air blast passing over same. I therefore, do not claim such a combination broadly.

45 I claim:

1. In a grain-separating machine, a supporting-frame, an inclined reciprocatory sieve-shoe supported in said frame, a plurality of superimposed sieves in said shoe, a plurality of rotatable endless aprons supported on said frame and extending through the sieve-shoe, each apron being supported above and parallel to a sieve of said shoe, the lower laps of the endless aprons arranged to travel downwardly in close proximity to the upper surfaces of the sieves, the upper laps delivering grain to the upper ends of said sieves, a sieve cleaning rack carried by the supporting frame and extending through said shoe closely adjacent to the under surface of the lowermost sieve carried by the sieve-shoe. 50

2. In a grain separating machine a supporting frame, a pair of reversely inclined, superimposed, reciprocatory screen-shoes carried by said frame, a screen supported in said upper screen shoe, a pair of superimposed screens supported in said lower screen-shoe, a screen cleaning rack carried by the supporting frame and extending through said shoe closely adjacent to the under surface of the screen carried by the upper screen shoe, a grain discharge board in said upper screen shoe, a transverse trough carried by the supporting frame below and parallel to the outer edge of said discharge board, a two-way conveyer in said transverse trough, a down spout carried by each end of said trough, said down spouts each discharging upon the top of the lower screen of the lower screen-shoe. 55

3. The structure set forth in claim 2, including a fan-casing mounted on the supporting frame, opposite said screen shoes, a fan in said casing arranged to direct a blast of air longitudinally of and between said screen-shoes. 60
